UNITED STATES PATENT OFFICE.

OTTO SIEBENBRODT, OF CHICAGO, ILLINOIS.

LAMP STAND.

Application filed June 22, 1923. Serial No. 647,015.

This invention relates to a lamp stand provided with an adjustable canopy for the top which may be laterally adjusted in several directions.

5 The invention comprises the novel mechanism and combinations hereinafter described and more particularly pointed out and defined in the appended claims:

In the accompanying drawings, which 10 illustrate a preferred embodiment of this invention, and in which similar reference numerals refer to similar features in the different views:

Figure 1 is an elevational view of the 15 lamp stand.

Figure 2 is an enlarged elevational view of the lamp fixture with the lower part of the standard omitted.

Figure 3 is a top plan view of Figure 2.

20 Figure 4 is an enlarged elevational view of an adjustable bracket for supporting the canopy of lamp shade.

Figure 5 is a sectional view on the line 6—6 of Figure 4.

25 Figure 6 is an enlarged elevational view of the upper end of the stand.

Figure 7 is a view similar to Figure 4, but showing the opposite side of the bracket.

As shown on the drawings:

30 Referring now to the drawings, there is shown a tapered hollow standard 3 having a base 1. The hollow standard 3 is formed with converging walls and supports at its upper end a box-like container 7, the bottom 35 of which closes the top of the hollow standard.

A pair of oppositely extending arms or 40 brackets 8 integral with the walls of the container 7 or attached thereto form supports

45 for a pair of incandescent lamps 9, the wire conduits 10 of which extend through the bracket to the box-like container. The outer ends of the arms 8 extend upwardly and they are provided with supporting clips 11 which 50 are bolted or secured thereto. These supporting clips consist of vertical faces with parallel ears extending from the faces which straddle the ends of the arms 8 for receiving the attaching bolts or the like.

55 A bracket 12 is supported by each clip 11. The lower end of each bracket is in the form of an arcuate plate having an arcuate slot 13, which is provided with a notch at the central point of its inner surface to receive 60 a stud 14 projecting from the face of the clip. A pivot screw 15 extending through

a slot 16 in the bracket rotatably supports the same upon the clip. Above the arms 8, the brackets 12 are inwardly offset as shown at 12^a in Fig. 5, and the offset portion is 60 sunk or depressed so that the lower end thereof will overlap the adjacent portion of the bracket as indicated at 12^b whereby a seat for a lamp shade is provided. The offset portion 12^a is provided with a central 65 longitudinally extending slot 17 through which an adjustable screw 18 extends, which supports a narrow plate member 19 having an arcuate jaw or clamping member 20 extending at right angles to its upper end. 70 Near the upper end of the plate 19 there is a second adjustable screw 21 which extends through a short slot in a short plate 22 which normally rests upon the top of the bracket. The upper end of the plate 22 is 75 bent outwardly at right angles in the form of an arcuate jaw or clamping member 23 that overhangs the jaw 20 and cooperates therewith to clamp the lamp shade there- 80 with.

The lamp shade as illustrated in the present embodiment of this invention consists of a pair of spaced equal circular rings 24 and a smaller concentrically arranged ring 25 positioned thereabove, the three rings being 85 permanently connected together in such relation by pieces of wire 26 which may be welded or soldered to the rings in any well known way. The shade is supported by the brackets 12, the lower ring resting upon the 90 offset portions and the second ring being clamped between the jaws 20 and 23. By unloosening the screws 21 and sliding the plates 22 upwardly, the jaws will be sufficiently separated for the introduction of the 95 upper ring 24. After the introduction of the ring, the two plates are slid down to clamp the shade in position and the screw tightened. By unloosening the screw 18 the plate 19 may be vertically adjusted to adapt the 100 bracket for holding different sizes of shades, as is obvious.

A phonograph or the like may be suitably supported in the box container 7.

If access is desired to either of the lamps 105 on either side of the phonograph, it is only necessary to lift the bracket 12 to bring the stud 14 into the arcuate slot, and the bracket may then be swung to either side. Figure 2 shows the bracket and shade swung to 110 the right hand side, but it can be swung to the left hand side in like manner, the

arcuate slot being designed to allow an oscillation of 180° of the brackets.

From the foregoing, it will be apparent that I have invented a novel form of lamp stand and an adjustable bracket for supporting the canopy or shade, which may be tilted to either side to provide access to both sides of the stand.

I am aware that numerous details of construction may be varied through a wide range without departing from the principles of this invention, and I therefore do not purpose limiting the patent granted otherwise than necessitated by the prior art.

15 I claim as my invention:

1. In a device of the class described, a standard, arms extending from said standard, adjustable brackets pivoted to said arms and swingable through an arc of a circle, 20 said brackets having lower rests and upper adjustable clamping members for the purpose described.

2. In a device of the class described, a standard, arms on said standard, brackets 25 pivoted to said arms, said brackets having

lower arcuate slots with notches, studs on said arms projecting through said slots and adapted for seating in said notches for maintaining said brackets in vertical position, and adjustable means on said brackets for supporting a canopy.

3. In a device of the class described, a standard, arms on said standard, a bracket pivoted upon each of said arms and adapted to be swung in the arc of a circle, said 35 bracket having an upper offset end and a pair of relatively slidable clamping members secured to said end.

4. In a device of the class described, the combination with a lamp, of a shade therefor, a support for said shade comprising bracket members secured thereto and having notched arcuate slots, and means extending through said slots and adapted for locking and unlocking said supports by a vertical 45 movement of said bracket members.

In testimony whereof I have hereunto subscribed my name.

OTTO SIEBENBRODT.
